UNITED STATES PATENT OFFICE.

EUGENE GRAHAM ANDERSON, OF SEATTLE, WASHINGTON.

DISPLAY-TABLE.

1,353,208.

Specification of Letters Patent. Patented Sept. 21, 1920.

Application filed January 22, 1920. Serial No. 353,320.

To all whom it may concern:

Be it known that I, EUGENE GRAHAM ANDERSON, a citizen of the United States, residing at Seattle, in the county of King and State of Washington, have invented certain new and useful Improvements in Display Tables, of which the following is a specification.

This invention relates to display tables, and the primary object of the invention is to provide an improved display table for dry goods stores or the like which is so constructed as to permit the ready display of bolted fabrics.

A further object of the invention is the provision of an improved display table of the convertible type which can be either used as a flat top table for notions or the like, or as an elevated table with inclined sides for the display of bolted fabrics.

A further object of the invention is the provision of a table having an improved top embodying hinged leaves arranged to form a flat table top or to form supports for a central elevated table top, the elevated central table top being removable and arranged to form a shelf when the leaves are folded to form a flat table top.

A still further object of the invention is the provision of an improved display table of the above character which is durable and efficient in use, one that is simple and easy to manufacture, and one which can be placed upon the market at a reasonable cost.

Other objects of the invention will appear in the following detailed description taken in connection with the drawings, forming a part of this specification, in which drawings:

Figure 1 is a fragmentary side elevation of the improved table showing the leaves in their lowered position.

Fig. 2 is an end elevation of the same.

Fig. 3 is a fragmentary top plan view of the table showing the hinged leaves removed and the end panels arranged on the bracing structure.

Fig. 4 is an end elevation of the improved table showing the leaves in their raised position and supporting the central table top, the table being arranged for displaying bolted fabric.

Fig. 5 is a central transverse section through the table showing the same in position for displaying bolted fabrics.

Fig. 6 is an inner end elevation of the table showing the same with the top in its

lowered position and showing the adaptation of the invention to a half table for use against walls or other supports, and

Fig. 7 is a detail transverse section through the same showing the table top in its elevated position for displaying bolted fabrics.

Referring to the drawings, wherein similar reference characters designate corresponding parts throughout the several views, the letter A indicates the improved table, which can be made of any desired length or width and out of any preferred material, and includes the frame B and the top C.

The frame B includes the supporting legs 10 arranged in spaced pairs and braced intermediate their ends by transverse brace bars 11. The upper ends of the legs 10 are connected by longitudinal and transverse ledges 12 and 13, which form supports for the top C when the same is arranged to form a flat top table. The upper ends of the legs 10 are further connected and braced by diagonal extending cross braces 14 which are arranged in a plane below the upper surface of the ledges 12 and 13 and the diagonal braces form means for receiving and supporting the end panels 15, which will be hereinafter more fully described, when the table top C is folded to form a flat surface.

The table top C includes the leaves 16 and 17 which are connected at their outer longitudinal edges by hinges 18 to the upper ends of the legs 10. The outer longitudinal edges of the leaves 16 and 17 extend slightly beyond the sides of the frame, and carry the upwardly extending retaining flanges 19. Each leaf is adapted to extend to the longitudinal center of the frame and the inner edges of the leaves 16 and 17 abut, when the leaves are moved to their lower positions in engagement with the upper edges of the ledges 12 and 13 and form a continuous unbroken flat surface.

When it is desired to form a table with an elevated top having inclined sides for the display of bolted fabrics or the like, the leaves 16 and 17 are swung on the hinges 18 to an inclined position, as clearly shown in Figs. 4 and 5 of the drawings, and a central removable leaf 20 is placed in position on the upper edges of the leaves 16 and 17. The meeting edges of the leaves 16 and 17 are provided with lower rabbeted edges 21 and the central or removable leaf 20 has its longitudinal edges rabbeted as at 22 to

interlock with the rabbeted edges 21 of the leaves 16 and 17. When the leaves 16 and 17 are swung to inclined positions, the removable end panels 15 are brought into use and the same are of substantially truncated triangular form and their lower edges or faces carry dowel pins 23 which are adapted to fit in sockets 24 formed in the upper terminals of the legs. The upper edges of the 10 panels 15 also carry dowel pins 25 which are adapted to fit in suitable sockets formed in the lower surface of the removable central leaf or panel 20 so as to hold the same against movement in relation to the end 15 panel. The leaves 16 and 17 also carry adjacent to their ends depending ledges or guide flanges 26, and these flanges are adapted to engage the inner surface of the transverse ledges 13 and serve to form 20 means for preventing relative movement between the leaves and the frame. When the leaves are raised to an inclined position, the ledges of depending flanges 26 form means for receiving and engaging the end panel 25 15 and the removable central or top panel 15 also carries a depending flange or ledge 27 for engaging the end panel.

When the table is arranged for receiving bolted fabric, it is to be understood that 30 the bolts are arranged on the uppermost panel or central leaf 20 and the fabric is allowed to hang down over the inclined leaves 16 and 17 which permits the goods to be readily seen or handled by prospective 35 customers.

When the leaves 16 and 17 are swung to their lowered positions and the middle panel or central leaf 20 is removed, the same is placed on the top surface of the transverse brace bars 11 and the same forms a 40 shelf for receiving suitable articles.

In Figs. 6 and 7 is illustrated the form of the table when used as so-called half tables or wall tables and the same are constructed exactly the same as tables of full width as disclosed in Figs. 1 to 5 with the exception that a single hinged leaf 28 is provided, which is adapted to engage a wall or other partition when the same is in its 50 folded position on the ledges. An end panel and the cross panel or central leaves 29 and 30 are each formed only half as wide as the end panels 15 and the central leaf or top panel 20 for the full table and the top panel 55 or central leaf 30 is only provided with one rabbeted longitudinal edge 31 for engaging the rabbeted inner edge 32 of the leaf 28.

From the foregoing description it can be seen that an improved display table is provided for dry goods stores, which may either be used as a flat top table for notions or the like or as a raised top table with inclined sides for the display of bolted fabric.

Changes in details may be made without

departing from the spirit or scope of my 65 invention; but,

I claim:

1. A display table comprising a lower frame and a top including a pair of leaves hingedly connected to the frame, a removable leaf carried by the hinged leaves, and removable end panels arranged to engage the frame and the leaves.

2. A display table comprising a lower frame, a pair of leaves hingedly connected at their outer longitudinal edges to the longitudinal edges of the frame, angular retaining flanges secured to the outer longitudinal edges of the leaves, the inner edges of the leaves being rabbeted, the leaves being adapted to lie flat on the upper surface of the frame or at an angle thereto, and a removable central leaf having rabbeted longitudinal edges arranged to interfit the rabbeted inner edges of the leaves when the same are arranged at an inclined position to the supporting frame.

3. A display table comprising a supporting frame, and a top including a pair of leaves hingedly connected at the longitudinal upper edges of the frame, arranged to lie flat on the upper surface of the frame or at an angle thereto, and a removable center leaf arranged to engage the inner edges of the leaves, when the same are arranged at an angle to the frame, and transverse bracing strips carried by the frame arranged and disposed intermediate the upper and lower ends thereof to receive the center leaf when the hinged leaves are swung in engagement with the upper surface of the frame.

4. A display table comprising a supporting frame, and a top including a pair of leaves hingedly connected to the upper longitudinal edges of the frame and arranged to lie flat on the upper surface of the frame or at an angle thereto, truncated triangular removable end panels arranged to be carried by the frame and support the leaves at an angle to the frame, and a removable center leaf arranged to engage the inner edges of the leaves and the panel when the leaves are arranged at an angle to the frame.

5. A display table comprising a supporting frame, and a top including a pair of leaves hingedly connected at their longitudinal outer edges to the upper longitudinal edges of the frame, and arranged to lie flat on the upper surface of the frame or at an angle thereto, removable truncated triangular end panels carried by the frame and arranged to support the leaves at an angle to the frame, retaining ledges carried by the lower surface of the hinged leaves and arranged to engage the end panels when the leaves are in their inclined positions or to engage the frame when the leaves are laid flat on the upper surface of the frame, and

a removable central leaf arranged to engage the end panels and the inner edges of the leaves, the center leaf having a depending ledge carried by each end for engaging the 5 panel.

6. A display table comprising a supporting frame including supporting legs, transverse brace bars connecting the legs, and diagonally extending cross braces connecting 10 the legs and arranged below the upper edges thereof, and a table top including leaves hingedly connected to the upper longitudinal edges of the frame and arranged to lie flat on the upper surface of the frame at an 15 angle thereto, removable end panels carried by the frame and arranged to support the leaves at an angle to the frame, and a removable center leaf carried by the panels

and arranged to engage the inner edges of the leaves, the end panels being adapted to 20 be supported by the diagonal braces when the leaves are laid flat on the upper surface of the frame.

7. A display table comprising a lower frame, a leaf hingedly secured to the frame, 25 removable end panels associated with the frame and leaf, a removable top leaf adapted to engage the upper surface of the end panels and the inner edge of the first mentioned leaf, depending ledges carried by 30 the leaves arranged to engage the inner faces of the end panels, and dowel pins carried by the end panels arranged to engage the top leaf and the frame, whereby the displacement of the end panels is eliminated.

EUGENE GRAHAM ANDERSON.
